(57) **CLAIM**

The ornamental design for a television receiver as shown and described.

DESCRIPTION

FIG. 1 is a front, right, top perspective view of a television receiver showing our new design;

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom plan view thereof;

FIG. 8 is a rear, right, top exploded perspective view thereof; and,

FIG. 9 is a rear, right, top perspective view thereof in a second state of use in an open configuration.

The broken lines depict portions of the television receiver that form no part of the claimed design.

1 Claim, 9 Drawing Sheets
